CLAIM

The ornamental design for a ski jump track apparatus, as shown and described.

DESCRIPTION

FIG. 1 is a top plan view of the novel ski jump track apparatus;

FIG. 2 is a side (either) elevational view thereof, the opposite side being a mirror image thereof;

FIG. 3 is a bottom plan view thereof;

FIG. 4 is a front elevational view thereof;

FIG. 5 is a rear elevational view thereof; and,

FIG. 6 is a perspective view of the novel apparatus.

FIG.1

FIG. 2

FIG. 3

FIG. 6

FIG. 4

FIG. 5
